(57) **CLAIM**

The ornamental design for a sandwich cooler container, as shown and described.

DESCRIPTION

FIG. 1 is a front perspective view of a sandwich cooler container, showing my new design;

FIG. 2 is a front elevation view thereof;

FIG. 3 is a rear elevation view thereof;

FIG. 4 is a right side view thereof;

FIG. 5 is a left side view thereof;

FIG. 6 is a top plan view thereof;

FIG. 7 is a bottom plan view thereof; and,

FIG. 8 is a cross-sectional view taken along lines 8-8 of FIG. 6.

The sandwich bag shown in broken lines in FIG. 1 represents environment and forms no part of the claimed design. Line shading and stippling in FIGS. 1, 6 and 8 have been used to indicate a contrast in appearance.

The broken lines in FIG. 8 represent portions of the sandwich cooler container and form no part of the claimed design.
